FOUNTAIN PEN

Filed Dec. 14, 1951

Inventor
Jorge S. Zarur,

By *Johnnie*
Johnnie Attorney

1. A fountain pen of the class hereinbefore described, characterized by a tube or tank having at one end a pen point and at the other end an ink-filling device, the tube being provided with a cover for the pen point and the pen-holding part removed, the cover being provided with a flared portion and having a passage therethrough, the tube being provided with a piston or stem having a flared portion and having a passage therethrough, the piston being provided with a plug having channels or passages, the piston being introduced through the mouth of the tube before adjusting the pen point and the pen holder.

UNITED STATES PATENT OFFICE

2,646,777

FOUNTAIN PEN

Jorge S. Zarur, Monterrey, Mexico

Application December 14, 1951, Serial No. 261,671
In Mexico December 28, 1950

1 Claim. (Cl. 120—47)

1. The present invention relates to the manufacture of fountain pens in general and more particularly to novel and useful improvements in such manufacture, intended to provide articles of the class aforesaid, characterized by great simplicity of construction, a large ink-filling capacity, and substantially by the fact that the filling operation is effected through the part of the tube opposite that which carries the pen point, by means of a novel, highly efficient, and small suction and discharge pump.

For the purpose of allowing the filling or ink-loading operation of the pen of the invention to be effected rapidly and without the user's staining his hands, said pen comprises in combination, an ink tube or tank, which carries at one of its ends the pen point and the pen-holding part and, at the other end, the ink-loading device; an outer cover for said tube or tank; and the usual cover, generally provided with a fastener or clip for securing the pen in position in a pocket.

In the present invention, the filling of the tube or tank is effected by the action of a novel pump, that is simultaneously for suction and discharge and which permits of obtaining a full supply of ink, completely filling all the tube or tank, even though the ink be at a low level in the ink well.

Since the tube will generally be made of transparent plastic material, the action of the pump can be perfectly regulated to suspend said action at the moment the ink completely fills the tube or tank, which allows of taking from the ink well only the exact amount of ink required.

The characteristic features of the invention and the advantages thereof will be made clearly apparent in the following description, as likewise in the drawings attached as an illustration of said invention, in which drawings the same reference numbers have been used to designate the same parts in the six figures shown.

In said drawings:

Fig. 1 is a side elevation of a fountain pen constructed in accordance with the invention, with the cover for the pen point and the pen-holding part removed.

Fig. 2 is a side elevation of the cover for the pen point and the pen holder.

Fig. 3 is likewise a side elevation, in longitudinal section, of the cover for the tube or tank of the pen.

Fig. 4 is a longitudinal sectional elevation of the tube or tank of the fountain pen of the invention, provided at one end with the pen-holder

and the pen point and, at the other end, with the filling device.

Fig. 5 is a detail of Fig. 4, showing more clearly the device for filling the tube or tank; and

Fig. 6 shows partially in elevation and partially in longitudinal section the different parts forming the fountain pen proper, namely the pen point, the pen-holder, the tube or tank, and the parts of the device for filling said tank.

10 Before describing in detail the fountain pen of the invention, I wish it to be clearly understood that the drawings illustrate only by way of example one of the ways of carrying out the invention, without limiting the latter to the specific 15 details illustrated and described, wherefore in the practice thereof recourse may be had to such variations and modifications as be considered or become necessary, without further limitation than the scope of the appended claim.

20 As illustrated in the drawings, the fountain pen of the invention comprises a tube or tank 10, of an appropriate shape, for example that usually employed, with its ends 11 and 12 open, as is shown more clearly in Fig. 6. At a point 25 closer to its end 11 than to its end 12, said tube 10 is provided with fastening ring 13 and thread 14, the latter serving to secure, by means of the internal thread 18, the outer cover 15, which forms hollow portion 39, which is closed at one 30 of its ends 16 and open at the other to form mouth 17. Fastening ring 13 is intended to secure cover 19, which is provided with the usual clip 20, when said cover is mounted upon step 21 of cover 15.

35 At end 11 of the tube or tank 10 is provided the pen point 22, which is held in operating position by pen-holder 23, provided with the split portion 24 so that the ink may flow over the writing point of said pen point. At its other end 12, tube 10 40 bears the ink-filling device, which constitutes the basic feature of the fountain pen of the invention and which is constituted by a double-action pump, for suction and discharge, comprised by a tubular piston or stem 25, with one of its ends closed 45 and having flared portion 26, and the other end being provided with thread 27, said piston or stem 25 having perforations 28 and 29 which connect the interior of the passage of the widened or flared portion and the interior of passage 30 of the stem, with the outside. At the mouth of the flared portion 26 is provided a plug 31, which retains therein small sphere 32. Plug 31 is formed with channels or passages 33. Said piston 25 is introduced through mouth 11 of tube 10, before 50 adjusting the pen point 22 and the pen holder 55

23, in such a manner that flared portion 26 remains inside hollow portion 38 of said tube 10 and the rest of the stem protrudes through mouth 12 of the tube. Around stem 25 is disposed antagonistic spring 34, which thus is positioned between the end of tube 10 and supporting part 35, likewise hollow, which by means of internal threading is secured to thread 27 on stem 25. Inside said hollow part 35 is positioned another small sphere 36, properly dimensioned for obstructing when necessary passage 37, through which passage 30 in stem 25 is extended to the outside. For proper adjustment of flared portion 26 of stem 25, there is provided on the inner wall of end 12 of tube 10, a washer or packing 40, of rubber or other suitable material.

Operation of ink-filling device

The device which the present invention provides for effecting the ink-filling operation, as a substantial part of said invention, operates as follows: After removing outer cover 15 from tube or tank 10, said tube 10 is introduced into the ink-well or other container for the ink to be used, with pen-point 22 positioned upwardly; in other words, said tube 10 is introduced into the ink supply by its end 12, until part 35 strikes the bottom of the ink container. Pressure is then exerted on tube 10 so that as a result of said pressure and upon overcoming the resistance of antagonistic spring 34, tubular stem 25 will slide inside hollow portion 38 in said tube 10, thus forming a vacuum, which causes the ink to be suctioned up through passage 37 and toward passage 30, from which it cannot escape because the small sphere 36 acts as a suction valve, preventing the ink from running out. Upon cessation of the pressure on tube 10, antagonistic spring 34 causes piston or stem 25 to return to its initial position. Upon repeating the operation, that is, upon exerting pressure anew on tube 25, the ink which is suctioned anew toward passage 30, forces the ink which had been retained therein, to be expelled through orifice or perforation 29, toward the inside of hollow portion 38 of tube 10, but below flared portion 26 of stem 25, which has been shifted toward the inside of said hollow portion 38. When the pressure on tube 10 is again released and spring 34 forces stem 25 and flared portion 26 to return to their original position, the ink which then is already in the lower portion of hollow part 38, flows through orifice 28 toward the inner passage of said flared portion 26 and from there, through passages 33, to the ink tank proper, formed by all of hollow portion 38. Con-

stant repetition of the pumping operation aforesaid causes tank 38 of tube 10 to become full of ink, and as preferably said tube will be made of transparent plastic material, the progress of the ink-filling operation can be observed, in order to stop the pumping at the proper moment. The ink which is already in the tank cannot flow out of it, due to the action of small sphere 32 which acts as a suction valve.

Having thus described the invention, what I consider as new and desire to secure by Letters Patent is:

A fountain pen comprising a hollow stem forming a reservoir open at opposite ends, with a pen point at one end and an ink supply pump at the opposite end, said pump structure comprising a piston head having a reduced portion to form a space in the reservoir and formed with a central chamber with a duct which communicates at one end with the reservoir through openings formed in the head and communicates at its opposite end with the reservoir through the space formed by the reduced end, a check valve in the chamber, the piston having a stem formed with an inlet duct open at its inner end to communicate with the reservoir when the piston is advanced to supply ink, packing in the end of the reservoir to seal the inlet duct when the piston is at rest, a hollow cap fitted on the free end of the stem, said hollow cap having an inlet opening at its free end, a check valve in the hollow cap for closing the inlet opening, a spring on the stem between the end of the hollow stem and the hollow cap to normally project the reduced end of the piston against the packing to close the inner end of the duct in the stem, whereby when the end of the hollow cap is held in an ink receptacle, and the hollow stem is forced against the tension of the spring, ink will be sucked in the hollow cap, through the duct in the stem to the space between the head and the reservoir wall and thence through the duct in the head, the valves in the head and in the hollow cap being opened by the suction created by movement of the piston to permit passage of the ink.
